UNITED STATES PATENT OFFICE.

CHARLES L. FOWLE, OF DOWAGIAC, MICHIGAN, ASSIGNOR TO THE DOWAGIAC MANUFACTURING COMPANY, OF SAME PLACE.

SHOE FOR GRAIN-DRILLS.

SPECIFICATION forming part of Letters Patent No. 411,141, dated September 17, 1889.

Application filed August 22, 1888. Serial No. 283,502. (No model.)

To all whom it may concern.

Be it known that I, CHARLES L. FOWLE, a citizen of the United States, residing at Dowagiac, county of Cass, State of Michigan, 5 have invented a new and useful Shoe for Grain-Drills, of which the following is a specification.

The object of this invention is to construct a drill-shoe which will deliver the grain below 10 the surface of the soil horizontally rearward into the furrow made by said shoe.

Other objects will appear set forth in the following description.

In the drawings forming a part of this specification, Figure 1 is a side elevation, parts being broken away; and Fig. 2 is an elevation looking from a point at the left of Fig. 1.

Referring to the lettered parts of the drawings, the hole E through the shoe A terminates through the rear below the surface-line xx' of the ground at E'. Thus the grain is delivered horizontally into the furrow immediately in the rear of said shoe before the dirt can fall into the furrow. The mouth E' 25 of the hole may all be below the surface of the ground or just that part through which the grain flows.

The shoe has the ordinary lugs F, for attaching lifting-chains to in the ordinary manner.

The base of the shoe which makes the furrow is faced on each side with steel plates B, converging toward the lower side, thus being V-shaped in cross-section or when looking against the end, as in Fig. 2. A wedge-shaped 35 bar D is welded in between the plates B, and the mouth E' of the hole E comes to the top of the wedge. If it were not for the wedge-

shaped bar D, the plates B would touch each other and be welded for some little distance up from the lower side, thus making this part 40 of the shoe narrower, which would not be desirable for the reason that the furrow would be of insufficient width below the discharge E' to allow the grain to fall freely to the bottom of the furrow. Then by employing the 45 bar D the device is strong and light, and comparatively light-weight steel can be used for the plates. These plates B are attached to the shoe by rivets G G' G'', or by other suitable means. 50

The upper part of the shoe is frequently called the "hopper," and the lower part, that forms the furrow, is called the "shoe;" but for convenience I have termed the whole device a "drill-shoe." 55

The draw-bar C is shown broken; but as it is well understood how drill-shoes are attached to the wheeled frame of a drill no particulars are here given.

Having thus described the invention, what 60 I claim, and desire to secure by Letters Patent of the United States, is—

A drill-shoe having the side plates converging at the base and a wedge-shaped bar attached between the plates at said base, substantially as set forth. 65

In testimony of the foregoing I have hereunto subscribed my name in presence of two witnesses.

CHARLES L. FOWLE.
